FEEDING MACHINE.

Application filed November 23, 1922. Serial No. 602,687.

This invention relates to a feeding machine and, more particularly, to a machine for feeding unbound bundles or groups of folded boxes or cartons or similar articles from a forming or gluing machine to a tying machine in which they are bound into packages suitable for packing.

Cartons and boxes of this type are commonly produced in a flat, folded form by a gluing machine from which they are delivered on a conveyor in a flat overlapping position. The boxes are counted into groups of fifty or other number suitable for packing by a counting mechanism which offsets each fiftieth box as it is delivered to the conveyor. These groups of boxes are then separated at the offset boxes by an operator, taken from the conveyor, formed into compact packs or batches, passed over a trip mechanism of a tying machine and held in position until bound into compact bundles suitable for packing and shipping. These various manual operations between the gluing machine and the tying machine require considerable time, even when they are distributed among several operators, and the boxes are therefore tied at a much slower rate than that at which they can be produced by the gluing machine. As a result, the gluing machine must be slowed down to the speed of the tying operations and the output correspondingly decreased. Moreover, whenever the tying of the bundles lags behind their production by the gluing machine, the boxes accumulate at the delivery end of the gluing machine, which must then be shut down until the accumulation of boxes can be bound. When such an accumulation occurs, there is also a tendency for the seams of the outer boxes of the packs to open as they lie in a loose condition between the gluing operation and the tying operation, thereby rendering these boxes worthless.

An object of the present invention is to provide an apparatus by which groups or batches of articles, such as flat cardboard boxes, may be automatically fed to, and carried through, a tying mechanism at a uniform, rapid, rate.

Another object of the invention is to provide a feed apparatus for tying and similar machines by which the feeding of batches of articles to the tying machine may be ac-

curately timed to the rate of supply or production of the articles.

Further objects of the invention are, to provide a simple and effective holding means for carrying flat boxes in compact batches and to provide a means for feeding batches of flat boxes or similar articles through a tying mechanism and timing the movement of said batches to hold them in proper position for tying and for adjusting the position of said tying mechanism to said timing.

With these and other objects in view, the invention comprises the apparatus described and set forth in the following specification and claims.

The various features of the invention are illustrated in the accompanying drawings, in which:

Fig. 1 is a side elevation of a feeding mechanism embodying a preferred form of the invention, and portions of the delivery belt of a gluing machine and of a tying mechanism,

Fig. 2 is an end view of the feeding machine shown in Fig. 1, looking from the direction of the gluing machine, portions of the mechanism being broken away to more clearly illustrate its construction,

Fig. 3 is a plan view of the end of the feeding machine near the gluing machine,

Fig. 4 is a side view of the driving mechanism of the feeding machine, taken from the opposite side of the machine,

Fig. 5 is a detail sectional view of a travelling chain conveyor and track forming part of the feed mechanism,

Fig. 6 is a detail view of a portion of the holding means for the batches of boxes, and,

Fig. 7 is a detail sectional view of a brake device for the batch or holder carrying means.

In the present invention, the operator need only remove batches of the desired number of boxes from the delivery belt of a gluing machine and place them in a holding device or holder of the feeding machine. Each batch of boxes is tightly held in the holder and moved by a suitable conveying mechanism in a short, rapid, movement until it passes and releases a trip mechanism of a tying machine positioned to be engaged by the passing batches. The further movement of the batch is then arrested until the

tying operation is completed. As this holder is brought to rest during the tying of its batch, a succeeding holder is brought into position to receive a second batch of boxes. 5 When the tying of the first batch is completed it is moved or is conveyed in its holder to a position to be removed while the succeeding holder is brought into position for the tying of its batch. There is thus a 10 constant succession of holders brought into position to receive a batch of boxes, conveyed into position to be tied and held in this position until tied, and then removed. As the movements required of the operators 15 of the machine are very simple they may be made very rapidly and the machine run at as rapid a speed as the gluing machine and tying machine will permit. To insure the feeding and tying of the boxes as soon 20 as they leave the gluing machine, the feeding machine is driven from a source common to the gluing machine or, preferably, it is driven directly from the delivery belt of the gluing machine and is run at a speed 25 sufficient to feed the boxes at a rate equal to, or slightly greater than, that at which they are supplied from the gluing machine.

Referring, more particularly, to the accompanying drawings, a batch 10 of boxes 30 to be bound or tied into a bundle is removed from a delivering conveyor 12 of a gluing machine and placed in position between spaced upright arms 14 and 16 of a holder mounted on endless conveyor chains 18 and 35 20. Each chain is provided with a pair of upright or outwardly projecting arms 14 and 16 for each holder and the batches of boxes or other articles to be bound or tied are firmly held in position between these 40 arms and extend crosswise between the chains as shown in Figs. 2 and 3. The chains are supported in parallel positions on tracks 22 and 24 mounted on a supporting frame 25 to extend substantially horizontally between driving cog wheels 26 and 28 supported on a driving shaft 30, and supporting wheels 32 supported on a shaft 34 at the other end of the frame 25. From the wheels 32 the chains return beneath idler wheels 36 to the driving wheels 26 and 28.

The chains 18 and 20 are driven at successive intervals to carry the holders from the position in which they receive the batch 10 to the position, indicated in Fig. 1, of a preceding batch 38. In passing to this position the batch engages and displaces a string 40 suspended from a needle 42, placed above the path of the holders, to a knotting and cutting device 44, placed between the tracks 45 22 and 24. As the batch passes over the knotting device it depresses a trip or trigger 46, which projects slightly above the level of the tracks, and, immediately upon reaching a position at which the trip is released, 60 the movement of the chains and holders is

arrested and the batch is stopped in position to be tied. As the trip mechanism is released, the needle 42 is depressed by the tying mechanism until it reaches the knotting device 44, drawing the string 40 tightly 70 about the batch and binding the batch into a compact bundle. Any suitable tying or binding machine may be used for this purpose and, as the construction of these machines is known, the position of the machine relative to the tying machine is merely indicated in the drawings. When the tying operation is completed, the chains and holders are moved to bring another batch of boxes into position to be tied and the tied 75 bundle is carried to the position of a preceding bundle 48, in which position it may be removed from the machine.

To enable the batches of articles to be readily inserted or placed in the holders and to be firmly and compactly held, the upright arms are provided with movable, parallel, holding bars 49 as shown in detail in Fig. 6, supported rearwardly of the arms 16 by means of bolts 50 and resiliently pressed away from the arms 16 by means of springs 51 inserted therebetween. To facilitate the insertion of batches of boxes the upper end of the bar 49 is rounded forwardly. The arms 14 and 16 may be supported on the chains 18 and 20 in any suitable manner, as for example, in the form shown in the drawings, by riveting or bolting the arms individually at suitable intervals in the length of the chain, to upwardly projecting seats 52 of supporting links.

The batches or bundles are thus carried in a regular, uniform, sequence from the receiving position to the tying position and the rate of their passage may be controlled by the driving of the shaft 30 and the wheels 26 and 28. As the placing of the batches in the holders and their removal from the opposite end of the machine require but very little time, the speed at which the machine may be run is limited only by the time required to operate the tying machine. The driving shaft is therefore driven at a definite ratio to the operation of the gluing machine, preferably, as shown in the drawings, by driving it from the delivery conveyor through a suitable transmission mechanism and the intermittent motion of the holders and chains is obtained in this transmission mechanism.

To this end, the delivery conveyor 12 of the gluing machine is provided with a sprocket wheel 53 which is arranged to drive a sprocket 54 of the feeding machine through a chain 55. The wheel 53 is splined to a shaft 56 which also carries a clutch member 58 adapted to engage a clutch member 60 secured to a gear wheel 62 mounted loosely on the shaft 56. The gear wheel 62 is provided throughout a portion of its circum-

ference with gear teeth 64 adapted to engage a spur gear 66, mounted on a stub shaft 67 extending from the side of the frame 25. The remaining portion 65 of the wheel 62 is without teeth and free to rotate without engaging or driving the spur gear 66. The spur gear 66, in turn, engages and drives a second gear 68 rigidly mounted on the shaft 30, the shaft 30 and its sprocket wheels 26 10 and 28 and the chains 18 and 20 being driven from the wheel 62 through the spur gears 66 and 68.

The wheel 62 and the intervening spur gears 66 and 68 are so positioned that, as 15 the last of the teeth 64 pass out of mesh with the spur gear 66, the chains and holders are brought into the position shown in Fig. 1, one of the holders having just cleared the trip 46 of the tying machine while the 20 following and preceding holders are in position to be loaded and unloaded, respectively. As the portion 65 of the wheel 62 rotates past the spur gear 66, the gears 66 and 68, and the chains and holders are held in stationary 25 position, the length of the toothless portion of the wheel being such as to provide sufficient time for the tying of a bundle. As the toothed portion of the wheel 62 approaches and engages the spur gear 66, the 30 movement of the chains and holders is resumed and the chains are driven to bring another batch of boxes into position to be tied. To insure the proper engagement of the spur gear 66, the wheel 62 is provided 35 with a short radially extending projection 70 adapted to engage a longitudinally projecting pin 72 on the gear 66 and bring the teeth of the gears into mesh. The gear 40 train and transmission mechanism between the gear 50 and the gear 68 are so arranged that the wheel 62 will be rotated and the holders advanced one position when the belt 12 has been advanced a length holding sufficient boxes for one batch or bundle. In 45 the embodiment of the invention shown in the accompanying drawings, the ratio of rotation of the wheels 52 and 50 is twelve to nine, but this ratio may be changed to suit conditions.

To insure the prompt stopping of the chains and holders as the untoothed portion 65 of the gear 62 reaches the spur gear 66, the shaft 30 is provided with a brake having 55 sufficient frictional resistance to stop the shaft as soon as the driving of the gear wheels 66 and 68 ceases. For this purpose, a reversely bent strip of metal 74 is mounted on the frame 25 by means of a screw or bolt 60 76, as shown in detail in Fig. 7, the reversely bent portion of the strip extending around and over the shaft 30. A strip of leather 78 or other suitable friction material is inserted between the strip 76 and the shaft 65 30 and the friction on the shaft may be ad-

justed by pressing the reversely bent portion of the strip toward the straight portion of the strip by means of a screw 80 threaded in the straight portion of the strip and having its head engaging the opposite 70 side of the reversed portion of the strip. A spring 82 is placed between the opposed sides of the strip to press them apart as the screw 80 is loosened.

When it is desired to stop the binding or tying of the boxes without stopping the gluing machine, the clutch member 58 is slid longitudinally on the shaft 56 until it is disengaged from the clutch member 60. To this end, the clutch member 58 is provided with an annular groove 84 rotating between forked arms 86 of a shifting lever 88 pivoted on a bracket 90 on the side of the frame 25. The groove is freely rotatable between the arms 86 but the sides of the groove are engaged as the lever 88 is tilted to either side to shift the clutch member. The lever is provided with a handle 92 by which it may be manually tilted.

The frame 25 may be of any suitable construction, preferably so arranged that the tying machine may be readily inserted into position and removed. The shafts 30 and 34 are mounted in bearings 94 and 96 at 95 opposite ends of the top portion of the frame and the tracks 20 and 22 are supported above the top of the frame in line with the upper surface of the wheels 26 and 32 by means of cross bars or brackets 98. The idlers 36 are journaled in bearings 100 supported in a vertically slidable relation on brackets 102 attached to the top portion of the frame 25. The vertical position of the bearings 100 may be adjusted by means of 100 screws 104 to tighten or loosen the chains 18 and 20. The frame is also, in its preferred form, so constructed as to permit the tying machine to be readily inserted in position with the trip and knotting mechanism in 105 proper position between the tracks 20 and 22 and to permit the position of the tying machine to be adjusted longitudinally of the tracks and conveyor chains to bring the trip mechanism into the proper relation to 110 the stopping point of the holders.

Through the above invention the batches or groups of boxes from the gluing machine are fed to the tying machine automatically in a rapid, uniform manner. The boxes are 120 bound and held in compact position as soon as they come from the gluing machine, thereby eliminating any tendency for them to come apart. The gluing machine may also be run at a much higher speed and its output correspondingly increased over that obtained when the boxes are fed to the tying machine by hand. It is understood however that the invention may be applied to other uses of a similar nature without de- 125 130

parting from the broader features of the invention.

Having described the invention what we claim and desire to secure by Letters Patent is:

1. Apparatus of the type described which comprises, means for receiving and holding groups of articles in a compacted form suitable for binding in packages, said means comprising a pair of spaced uprights and a resiliently pressed upright therebetween, means for banding said groups in packages, and means for intermittently moving said packages in a continuous path to cause said groups to pause in position for banding and to thereafter continue in an unchanged direction on their paths.
2. Apparatus of the type described which comprises, holders for holding articles in compact groups for tying into packages, a chain conveyor for carrying said holders into position for the tying of said articles, supporting and driving sprockets for said chain conveyor, a driven gear in driving relation to said sprockets, and a driving gear having teeth on a portion of its circumference to mesh with said driven gear and being free of teeth on the remaining portion of its circumference.
3. Apparatus of the type described which comprises, holders for holding articles in compact groups to be tied, chain conveyors for carrying said holders, tracks supporting said chain conveyors and arranged to permit the insertion of the trip mechanism of a tying machine therebetween, means for driving said chains on said tracks and interrupting the driving of said chains at uniform intervals to cause said groups to pause in position for tying.
4. Apparatus of the type described which comprises, holders for holding articles to be tied, conveyor means for conveying said holders through a position for tying said articles, a transmission gear for driving said conveyor means, a driving gear for said gear train having teeth on only a portion of its periphery, a finger on said driving gear, and a pin on the transmission gear adapted to be engaged by said finger when the teeth of said driving gear approach a position to mesh with the teeth of said driven gear.
5. Apparatus of the type described which comprises, holders for holding articles to be bound, chain conveyors for carrying said holders through a position for tying said articles, cog wheels and supporting and driving shafts for said chain conveyors, means for driving said shafts, means for interrupting the driving of said shafts at regular intervals, and a brake device for stopping the rotation of said shafts as soon as the driving means is interrupted.
6. Apparatus of the type described which comprises, an endless conveyor chain, a pair of outwardly extending arms mounted on successive links of said chain, and a bar resiliently mounted rearwardly of the first arm of said pair.
7. Apparatus of the type described which comprises, a machine for gluing boxes, a tying machine, means for holding batches of folded boxes from said gluing machine, an endless chain conveyor for carrying said holding means past said tying means, a gear wheel driven by said gluing machine, said gear wheel having teeth on only a portion of its circumference, and gears for driving said endless chain conveyor meshing with the gears of said gear wheel.

In testimony whereof, we affix our signatures.

WILLIAM E. TAYLOR.
ZIGMUND HOFFMAN.
